5 Claims. (Cl. 53—28)

This application is a division of copending application
10 Ser. No. 352,210, filed Mar. 16, 1964, now Patent No.
3,223,229.

This invention relates to methods of manufacturing
15 packages of the type comprising an envelope and a bag
enclosed therein, said bag containing a material, such as
tea leaves, for brewing a beverage. The manufacture of
such packages is involved with certain difficulties because
the package has to be constructed with a view of minimizing
20 the manufacturing cost. As a matter of fact the cost of
the bag and envelope embodied in such packages has
to be regarded as compared with the value of the portion
of tea or other material that is enclosed in the package
and constitutes the usable product thereof.

The object of the invention is to provide methods of
25 manufacturing such packages.

The method of manufacturing the package is characterized
by the steps of advancing a web of for instance
paper, folding the web preferably about a longitudinal
line, inserting bags provided with carrier strings successively
30 in a row between the portions formed by folding, and forming
an envelope around each bag by pressing said portions
together and interconnecting them both along two lines
extending transversely of the fold on either side of
the bag and at the edges parallel to the fold after inserting
35 the free end of the carrier string between said edges so as
to secure said string to the edges while they are pressed
together. To seal the bag, various kinds of binders may
be used, not only heat sensitive binders in connection with
heat sealing, but also contact adhesives which are cold
40 setting provided they are applied to both surfaces which
are to be brought into contact with each other.

An example of the application of the invention is illustrated
in the annexed drawing in which:

FIGURES 1 and 2 are diagrammatic and perspective
45 views of devices in two different steps of operation for
carrying out the method according to the invention; and

FIGURE 3 is a perspective view of an opened envelope
and a bag withdrawn therefrom.

In the embodiment illustrated it is assumed that the bag
itself which may contain tea leaves or the like for brewing
a beverage consists of a fabric or braid of plastics
threads and comprises two compartments 1, 2 in which
a portion of tea or the like is distributed. The compartments
50 are formed by interconnecting opposite walls of the bag
along a central transverse line 3 (FIG. 3). Midway of this connecting line the bag is connected to
the surrounding envelope 4 such as by means of a string
5 one end of which is secured to the bag and the other
end of which is secured to the envelope. To connect the
55 string with the envelope the end of the string is inserted
between two opposite parts of the walls of the envelope
as will be seen from FIGS. 1 and 2.

A web of paper or similar material is unwound from a
supply roll 7 and passed beyond a guiding and folding
device 8 by means of which the web or strip is folded
60 along a longitudinal central line so as to be doubled up.

2

Between the folded parts of the web which are to form
the front and rear sides of the envelope there is successively
6 inserted a plurality of bags provided with carrier
strings 5. The compartments 1 and 2 are preferably fac-
ing each other such that a substantial part of the string
will come to lie in the form of a loop between the compartments
while the free end of the carrier string is projecting
upwards between the upper edges of the compartments.
Preferably, at the same time a reinforcing strip 10 is
10 unwound from a supply roll 9 and advanced concurrently
with the web 6 adjacent to the longitudinal edges of the
folded parts. A binding agent may be applied to the web
6 and/or the reinforcing strip 10 on one or both sides
which are to be facing each other. After a plurality of
15 bags have been inserted between the walls formed by the
web 6 these walls are pressed together, by means of a
pair of backing plates 11, 12 or other members, along
two lines 14, 15 extending transversely of the fold of
the web 6 and at the longitudinal edges parallel to the
20 fold so as to form a label 18. The string 5 inserted
between the wall portions forming the label is clamped
between and connected with the wall portions when they
are pressed together. The backing plate 12 may be pro-
25 vided with transverse knives 16 and the backing plate 11
has corresponding incisions. When the backing plates are
moved together the knives 16 in cooperation with the
incisions 17 will separate from the web 6 envelopes for
the bags which have been inserted between the backing
30 plates. At the same time the envelopes are compressed
and sealed along three edges thereof.

If a package of the kind described is to be used for
brewing a beverage the label 18 is torn from the remainder
35 of the envelope which consequently will be opened. Then
the bag can be easily withdrawn from the opened envelope
by grasping the label 18 and pulling the bag out from
the envelope by means of the appendant string 5. The
label and the string are then used for immersing the bag
40 in the liquid for brewing the beverage.

In case of heat sealing for closing the envelope the
45 backing plates 11, 12 have to be heated to a suitable tem-
perature. If a cold setting contact adhesive is used the
backing plates may be cold. The devices illustrated in
the drawing are intended to be used for intermittent ad-
vance of the web 6 and the reinforcing strip 10 with the
length of each feed step corresponding to the width of
50 three packages, but within the scope of the invention any
desired lengths of feed steps are conceivable. Also con-
tinuous advancement is possible in connection with rotary
sealing members generally devised in the same manner as
the plates 11, 12. Even in other respects the invention is
55 not limited to the details illustrated.

What is claimed is:

1. A method of manufacturing packages for tea leaves and similar material, comprising the steps of advancing a web of paper, folding the web about a line at least substantially parallel with an edge of the web to form opposite walls, inserting bags each provided with a carrier string successively in a row between said opposite walls, inserting an end of each carrier string between said walls at edges thereof located opposite the fold, and forming an envelope around each bag by pressing portions of said walls together along two lines extending transversely of the fold on either side of each bag and at an edge of the walls parallel with the fold to unite the portions along said lines and to fasten the end of the carrier strings therebetween.
- 60 2. The method as claimed in claim 1, characterized by

applying a preferably heat sensitive binder at least to the surfaces of the web which after the folding operation are facing each other, and closing the envelope by hot pressing the parts to be interconnected.

3. The method as claimed in claim 1, characterized by inserting a reinforcing strip between said edges prior to compressing the edges.

4. The method as claimed in claim 1, characterized by heat sealing said envelope edges and connecting the end of each string to said edges by making the string of plastics so as to be softened while the edges are heat sealed.

5. The method as claimed in claim 3, and applying a binder to the reinforcing strip.
